ABSTRACT OF THE DISCLOSURE

The invention prevents damage to liquid or wet paper pulp by microorganisms and forestalls or destroys the microbic ooze that forms in the water of systems of paper mills by use of a composition comprising a mixture of (1) alkali metal or alkaline earth metal salts of di(lower alkyl) dithiocarbamic acid, chiefly alkali metal dimethyl dithiocarbamate, (2) alkali metal of (lower alkylene)-bis-dithiocarbamic acid, chiefly (ethylene) - bis - dithiocarbamic acid, and (3) a stabilizer consisting of 1,8,3,6 diendomethylene 1,3,6,8 tetraazacyclodecane, also known as 1,3,6,8 diendomethylene 1,3,6,8 tetraazacyclodecane.

This application is a continuation-in-part of our co-pending application Ser. No. 318,440, filed Oct. 23, 1962, now abandoned, in the names of Jean-Paul Pelissier and Pierre Chiffert.

This invention relates, by way of a new product, to a composition for protecting all industrial products liable to biological deterioration. In particular, the invention prevents damage to liquid or wet paper pulp by micro-organisms and forestalls or destroys the microbial ooze that forms in the water systems of paper mills. The invention also relates to the manner or methods of industrially using the composition.

In the manufacture of paper, large losses often result from the fermentation of wet cellulosic pulp. In addition, it is well known that the growth of various bacterial or fungal microorganisms presents serious problems in the manufacture of paper. Microorganisms cause the formation of microbial ooze in the water systems, resulting in clogging of the piping and in causing the band of paper either to break or to weaken, resulting in disruptions in the manufacture and a decline in the production.

To eliminate these drawbacks, various chemicals have been used, such as first chloramin, phenols, and chlorophenols, on the one hand, which have not given the anticipated results, and second organo-mercurial compounds, on the other hand, which have been most satisfactory, except for the drawback, among others, that they are toxic. It has been necessary, consequently, to pursue further research to find compositions that are efficacious but non-toxic.

The fungicidal and bactericidal properties of dithiocarbamates, certain of which are widely used in agriculture as anti-cryptogamous agents, in the form of insoluble salts of various metals, have long been known.

During their research, the inventors made the following unexpected discovery forming the basis of the invention: biological damage to industrial products, and particularly with regard to paper making treatments (damage to pulp, prevention or destruction of microbial ooze), can be avoided in a way that is at once advantageous

2

and thorough by treating the products with a stabilized or unstabilized mixture of water soluble salts of at least one mono- or dialkyl dithiocarbamic acid and of an alkylene-bis-dithiocarbamic acid. The soluble salts are particularly alkaline or alkaline earth salts, including ammonium or quaternary ammonium salts; the alkyl radical comprises one to three carbon atoms, and the alkylene comprises two or three carbon atoms. It has been found that the effectiveness of such a mixture is at least equal, and usually superior, to that of each of its parts taken separately. In other words, for reasons and in a way not yet clearly understood, the simple mixture of the two kinds of dithiocarbamates mentioned above causes a reciprocal reinforcement of their effects. It is observed that the compositions of the invention, when used for the purposes indicated, give rise to numerous advantages alongside their non-toxicness. On the one hand, the compositions do not leave toxic residues. On the other hand, the range of activity on the different bacterial or cryptogamous organisms is broadened. The action of the compositions increases normally with their concentration in the mass treated; that is, there are no "inversion zones" as there are with the constituents taken alone (the behavior of sodium dimethylthiocarbamate being well known).

The ingredients of the mixtures are:

(1) Alkyl dithiocarbamates having the formula

where:

R is an alkyl group having a low molecular weight (equal to or less than C_8):

R' is H or an alkyl group of low molecular weight; and M is an alkaline or an alkaline earth cation or a quaternary ammonium; and

(2) alkylene-bis-dithiocarbamates having the formula

where n is equal to 2 or to 3 and M has the same meaning as under (1).

The soluble salts of ethylene-bis-dithiocarbamic acid have shown themselves particularly advantageous within the scope of the invention.

A composition, which is especially effective, is a mixture of alkaline-dimethyldithiocarbamate and ethylene alkaline-bis-dithiocarbamate, the molecular proportions being varied from five to one or one to five.

The compositions obtained from the mixture are solutions that are generally stable under normal conditions for from two to six months. According to another object of the invention, their stability can be improved by adding the condensation product of ethylenediamine with methanal. Said product was prepared by Bischoff (Berichte 31-3254-1898). The quantity added may amount to 25% of the dithiocarbamic salts. It is interesting to observe that, even in the very large quantities indicated, the weak action of the stabilizer has no unfavorable effect on the activity of the composition.

A composition containing 10% to 25% of this additive remains stable for from 18 to 24 months under usual conditions.

The compositions of the invention are employed as aqueous solutions. They can be prepared either by mixing aqueous solutions of the various components of the composition, according the desired proportions, or by operating the reaction from a mixture of amines.

There will now be given a number of detailed examples of compositions of the invention, with the results ob-

Tables II and III show the bacteriostatic and bactericidal levels, respectively, with *Staphylococcus aureus*.

A. STAPHYLOCOCCUS AUREUS

TABLE IIa.—BACTERIOSTATIC TEST

Substance	Concentration in p.p.m. of active substance				
	40	20	10	5	1
PR ₁	0	0	0	0	Slight cloudiness ¹
Sodium dimethyl-dithiocarbamate	0	0	0	0	One-half of control culture ¹
Sodium ethylene-bis-dithiocarbamate	0	(1)	(1)	(1)	(1)

¹ Control culture: strong growth.

B. PSEUDOMONAS AERUGINOSA

TABLE IIIa.—BACTERIOSTATIC TEST

Substance	Concentration in p.p.m. of active substance				
	400	200	10	80	
PR ₁	0	0	0	(1)	
Sodium dimethyl-di-thiocarbamate	0	(1)	(1)	(1)	
Sodium ethylene-bis-dithiocarbamate	0	1/2 of control culture	(1)	(1)	

¹ Control culture: strong growth.

TABLE IIIb.—BACTERICIDAL TEST

Substance	Concentration in p.p.m. of active substance				
	800	600	400	200	100
PR ₁	0	0	0	0	1/4 of control culture ¹
Sodium dimethyl-di-thiocarbamate	0	0	(1)	(1)	(1)
Sodium ethylene-bis-dithiocarbamate	0	1/4 of control culture	1/2 of control culture	(1)	(1)

¹ Control culture: strong growth.

In another series of tests, realized in a different manner, one has first developed a culture of *Aerobacter aerogenes* on a meat broth and in its maximal phase of growth, one has seeded a new medium and effected the treatment with the products being at the desired concentration. The percent of mortality has been tested relatively to the concentration of active material. One has obtained the curves shown in the annexed drawing (with the concentrations in abscissae and the mortality in ordinates), respectively for product PR₁, sodium dimethyl-dithiocarbamate (I) and ethylene-bis-dithiocarbamate (II).

The different constituents and compositions were tested and compared under practical conditions, using a substratum of pulp first seeded with *Aerobacter aerogenes*. The results are arranged in Table IV.

(DMTCD). No control is obtained with product A. At 10 p.p.m., the product B gives total control. The synergism is evident.

TABLE V

15	Concen- tration in p.p.m. (dry mate- rial)	Millions of microorganisms per milliliter of fibrous suspension		
		1st day	2nd day	3rd day
Product A	1	134.5	70.0	75.5
	5	77.0	90.0	93.5
	10	0.5	82.0	70.0
Product B	1	120.0	96.5	112.5
	5	84.0	87.0	76.0
Control 1	10	0	0	0
Control 2	100.0	98.5	88.5	93.5
	100.0	86.0	86.0	97.5

It will be noted that the effect of an aqueous solution of DMTCD (1,3,6,8 diendomethylene 1,3,6,8 tetraazacyclodecane) was also investigated.

These results are strong evidence of the remarkable action of the compositions of the invention, in comparison with those obtained from the individual constituents and the stabilizer.

Finally, two ways of employing the compositions of the invention will be given by way of illustration.

EXAMPLE 4

The daily number of breaks was ten for a machine producing 200 kilograms of newsprint daily in a paper factory.

The ooze formed chiefly in the head box, in the slots

TABLE IV

Substance	Concen- tration in p.p.m.	Millions of microorganisms per milliliter of fibrous suspension, hours			
		24	48	72	144
PR ₁	5	0	0	0	0
	10	0	0	0	0
	25	0	0	0	0
	50	0	0	0	0
Sodium di-methyl-di-thiocarbamate	5	0.130	119.50	244.00	42.00
	10	0	0	111.90	85.00
	25	0	0	0	0
	50	0	0	0	0
Sodium ethylene-bis-dithio-carbamate	5	32.35	136.50	126.50	32.50
	10	6.00	126.50	143.50	26.50
	25	0	0	0	0
	50	0	0	0	0
PR ₃	5	0	0	0	0
	10	0	0	0	0
	25	0	0	0	0
	50	0	0	0	0
DMTCD	5	38.20	104.50	154	29
	10	21.65	111.00	118	37
	25	20.65	100.50	148	54
	50	0	0	0	0
Control Suspension 1	25.64	85.15	110.50	21.50	
Control Suspension 2	24.24	140.50	120.50	21.10	

In Table V, below, which is similar to Table IV, the product A consists of ethylene-bis-dithiocarbamate and di-methyl dithiocarbamate. The product B consists of product A + diendomethylene tetraazacyclodecane as stabilizer

of the Lamor screens, and on the walls of the back water box.

The PR 3 mixture was continuously added in the Four-75 drainer pit catching the water from the pulp, so that its

concentration in the water was from 0.2 to 1 p.p.m. The average number of breaks over a period of 15 days was reduced to one or two daily. Moreover, it must be noted that it was impossible to be certain that these breaks were caused by the formation of ooze.

EXAMPLE 5

In a paper factory using a Kraft paper machine producing 500 kilograms per day, the recycled water having a pH of 6.5 to 7, it was necessary to shut down the machine once every two days to clean the head water system of the machine. Adding the PR 3 mixture by means of the pulp dilution pump, at the rate of 1 to 3 p.p.m., completely eliminated any need for this cleaning.

We claim:

1. A bacteriostatic and bactericidal composition consisting essentially of (1) a water soluble salt selected from the group consisting of alkali metal and alkaline earth metal salts of alkyl dithiocarbamic acids, the alkyl group being of one to three carbon atoms, (2) a water soluble salt selected from the group consisting of alkali metal and alkaline earth metal salts of alkylene-bis-dithiocarbamic acids, the alkylene radical being of two to three carbon atoms, and (3) a stabilizer consisting essentially of 1,8,3,6 diendomethylene 1,3,6,8 tetraazacyclodecane, the molecular proportions between the alkyl dithiocarbamate and the alkylene-bis-dithiocarbamate varying from one to five and five to one by weight and the stabilizer being from 10% to 25% of the weight of the composition.

2. The composition of claim 1, wherein the alkyl dithiocarbamate is of the formula

where R is an alkyl group equal to or less than C_3 , R' is H or an alkyl group equal to or less than C_3 , and M is an alkali or alkaline earth metal substituent.

3. The composition of claim 1, wherein the alkylene-bis-dithiocarbamate is of the formula

5 where n is two or three and M is alkali or alkaline earth metal substituent.

4. The composition of claim 2, wherein the alkylene-bis-dithiocarbamate is of the formula

15 where n is two or three and M is as in claim 2.

5. The composition of claim 3, wherein a soluble salt of ethylene-bis-dithiocarbamic acid is employed.

6. The composition of claim 4, wherein there is a mixture of dimethyl dithiocarbamate and of ethylene-alkali metal-bis-dithiocarbamate.
